UNITED STATES PATENT OFFICE.

ARTHUR T. PRESCOTT, OF EAST ORANGE, NEW JERSEY, ASSIGNOR TO GEORGE H. FROTHINGHAM COMPANY, OF NEW YORK, N. Y., A CORPORATION OF NEW YORK.

DOOR.

1,274,443.

Specification of Letters Patent.

Patented Aug. 6, 1918.

Application filed April 10, 1916. Serial No. 90,045.

To all whom it may concern:

Be it known that I, ARTHUR T. PRESCOTT, a citizen of the United States of America, and a resident of East Orange, county of 5 Essex, and State of New Jersey, have invented certain new and useful Improvements in Doors, of which the following is a specification, reference being had to the accompanying drawings, forming a part 10 thereof.

My invention relates to doors and has special reference to large, heavy doors, such as are employed in factories, warehouses, pier sheds and the like. It furthermore, 15 specially pertains to doors having two or more sections, hereinafter referred to as multi-section doors, which are opened by first elevating one of the lower sections upon the section above and finally swinging the 20 overlapping sections into a horizontal or an inclined position above the door opening.

In doors of this character, difficulty has been encountered hitherto because the hoisting mechanism usually exerts forces in vertical planes and some means is consequently required to start the sections to swing inwardly,—in other words, to make the door “break in”. If, as has frequently been attempted, means are employed for positively 25 effecting the breaking in of the door, another difficulty develops, viz., that of tightly closing the door against the casing which is specially troublesome with large doors when closing in opposition to strong wind 30 pressure. It will be readily understood that the difficulties are so related to each other that any means which serves to overcome one, tends to increase the other.

It has been my aim to provide simple and 40 durable means for eliminating both of the above-named difficulties at the same time. In other words, to provide a suitable mechanism capable of being attached to a multi-section door and adapted to assist the breaking in of the door in opening and to positively hold the door tightly in its closed position when the door is shut.

My invention is by no means restricted to any particular door structure and its application to doors of various types will be 50 readily understood by those skilled in this art.

More specifically, one object of my invention is to provide an improved and effective mechanism dependent upon the normal 55

movement of one of the door sections in opening for causing the top of the door to swing inwardly so as to avoid undue strains upon the hoisting mechanism and so as to facilitate the opening of large, heavy doors. 60

Another object is to provide means for holding the top of the door firmly closed against the casing and to facilitate its closing under adverse conditions.

Another object is to provide a single 65 mechanism that shall be adapted to not only swing the top of the door inwardly when the door is being opened, but also to positively swing the top of the door closed when it is being shut.

Another object is to provide a simple and reliable mechanism for positively holding the door closed when once it is shut and dependent upon the upward movement of one of the lower door sections upon the section 70 above, not only for its release, but also for practically freeing the door entirely from its influence so as to remove the possibility of retarding the opening of the door particularly when it first starts to swing inwardly 75 at the top.

Other objects of my invention will be set forth hereinafter, and in order that my invention may be thoroughly understood I will now proceed to describe the same in 80 the following specification and then point out the novel features thereof in appended 85 claims.

Referring to the drawings:

Figure 1 is a front elevation of a door 90 which is arranged and constructed in accordance with and constitutes an embodiment of my invention.

A vertical section of the same door at right angles to Fig. 1, is shown in Fig. 2. 95

Fig. 3 is a view corresponding to Fig. 2, but drawn to a larger scale and showing the door with the bottom section folded upon the upper section.

Fig. 4 is a front elevation showing one 100 of the open and close mechanisms in front elevation, drawn to the same scale as Fig. 3.

Fig. 5 corresponds to Fig. 3, but shows the door in a slightly advance position, that is, with the upper end swung inwardly from 105 the easement to a slight extent.

Figs. 6 and 7 are sectional plan views, taken respectively on the lines 6—6 and 7—7 of Fig. 3.

Fig. 8 is a sectional elevation showing a 110

detail of one of the latches which form parts of the mechanism of the previous figures. This view is taken on the line 8—8 of Fig. 6.

A modification of my invention is shown 5 in Fig. 9, which corresponds to Fig. 3, Fig. 10 being a sectional plan view taken on the line 10—10 of Fig. 9 and corresponding to Fig. 7.

Still another modification of my invention 10 is shown in Fig. 11 which also corresponds to Fig. 3.

Fig. 12 is a sectional plan view on the line 12—12 of Fig. 11, and Fig. 13 is a plan view showing the same mechanism more 15 completely.

Fig. 14 closely corresponds to Fig. 2 and shows the mechanism of Figs. 9 and 10 as applied to a door of a different type. This 20 is for the purpose of indicating the scope 20 of my invention.

Special reference may first be had to Figs. 1 to 8 inclusive, although corresponding parts are designated by the same reference characters in all of the figures. The door 25 opening is defined by side posts 30 and a lintel 31. The door comprises an upper section 32 suspended from above the door opening by links 33, and a lower door section 34 to which hoisting chains or other 30 flexible cords 35 are connected. The upper section is provided with guideways 36 in which the lower section runs, the upward movement of the lower section on the upper section being limited in the usual manner 35 by pins 37 located near the lower corners of the lower section and extending beyond the guideways 36. Rollers 38 are mounted on the pins and coöperate in any suitable manner with the door posts 30 which may be 40 provided with guideways.

In opening the door the lower section slides upon the upper section until the two are overlapped; then the two sections together swing away from the lintel of the 45 door at the top until they occupy a substantially horizontal or an inclined plane.

My invention is applicable to doors which operate in substantially the manner just outlined irrespective of the means of support and the details of the structure.

The hoisting chains 35 coöperate with the sheaves 39 which are secured to a head shaft 40 and form parts of a suitable hoisting mechanism designated 41. Counterweights 55 42 are suspended from the opposite ends of the hoisting chains, the operation of the door being controlled by a hand chain 43. The hoisting mechanism as well as the details of the mounting of the door in themselves, form no part of my invention and are well known. In fact, my invention is particularly concerned with what may be termed a "break and close" mechanism 60 which is designated 44 and will now be described.

Two mechanisms will usually be employed as shown in Fig. 1 but the number is immaterial and will depend upon the size of the door. It is only necessary to describe 70 one in detail as they are identical and attention is particularly directed to Figs. 3 to 8. Secured above the door opening is a stationary guide bracket 45 having flanged ribs near its upper end constituting a guideway 46, and an outwardly extending hook 75 projection 47 at its lower end.

Pivotedly mounted on an extension 48 of the bracket is a release bar 49 which is held against a stop 50 by a spring 51 unless otherwise displaced. This bar is inactive 80 when the door is opening but, as explained hereinafter, has an important function in connection with the closing of the door.

The mechanism 44 in addition to the stationary bracket 45 and its attachments, 85 comprises a bracket 52 attached to the upper door section 32 near its upper end, a bell crank lever 53 and a latch 54 pivotally mounted on a common shaft or pin 55 of the bracket 52. As clearly shown in Fig. 6, the 90 latch 54 has a central recess 59 forming a pair of spaced hubs 60 between which a single hub 61 of the bell crank lever 53 is disposed, the bracket 52 being bifurcated to provide a pair of spaced bearings 62 in 95 which the pin or shaft 55 is supported.

The mechanism furthermore, comprises an actuating member 56 which is attached to the lower door section 34 near its upper end and is provided with a pivotal arm or 100 finger 57 which acts like a rigid lateral projection when the member is moving upwardly and the door is opening, and is pushed aside as hereinafter explained, in opposition to a spring 58 when the door is 105 closing and the lever is moving downwardly.

One arm 63 of the bell crank lever 53 is substantially perpendicular to the plane of the door when the door is closed, as shown 110 in Fig. 3, and the other arm is substantially upright but curves or extends inwardly at its upper end and terminates in a T-shaped extremity 64. As clearly indicated in Fig. 7, the arms of the extremity 64 are adapted to 115 engage the guideways 46, the arrangement of parts being such that when the door is nearly closed, the bell crank lever 53 swings about the extremity 64 as a pivot, and, by reason of the action of a powerful spring 120 65, tends to force the door into its closed position where it is held by the engagement of the latch 54 with the hooked projection 125 47 of the bracket 45.

The latch 54 is held in a set position by a spring 66, its engaging end 67 being beveled at 68 so that it is cammed past the hook projection of the bracket in a well-known manner.

The opposite arm of the latch 54 from the 130

engaging end 67 is adapted, when forced into its released position, to engage the arm 63 of the bell crank lever 53.

The bracket 52 is provided with an arm 69 which extends outwardly and upwardly from one of the hubs 62 and has an enlargement 70 at its outer end in which a pawl 71 is mounted to slide transversely. As shown in Fig. 8, this pawl is provided with an enlargement 72 at one end having a beveled surface 73 which is engaged by the end of the bar 49 as the door swings to its closed position. When the door is closed the bar 49, as clearly indicated in Fig. 3, rests upon the top of the enlargement 72 of the latch 71, being raised to this position in opposition to the spring 51 by the final closing movement of the door.

Before describing the other embodiments 20 of my invention, I will discuss the operation of the door and mechanism already described.

Assuming that the door is closed, as shown in Figs. 1 and 2, to open the door the hand chain 43 is operated in a well known manner to cause the lower section 34 to slide upwardly in the guideways 36 of the upper section. The member 56 now approaches the remainder of the mechanism 44, the parts 30 occupying positions substantially as shown in Figs. 3 and 4. A continued upward movement of the section 34 with the member 56, brings the arm or finger 57 into engagement with the outer arm of the latch 54, which is thus swung about the pin 55 as a pivot in opposition to the spring 66, until it engages the arm 63 of the bell crank lever 53. Still further upward movement of the door sections actuates the bell crank lever 53 40 which reacts upon the bracket 45 and as it swings, it forces the top of the door sections away from the lintel in an opening direction as shown in Fig. 5.

This action is a positive action and effectually "breaks in" the door so that a further upward pull transmitted to the door sections through the hoisting chains 35, readily causes the door to swing into its open position in which the sections are only 50 slightly inclined to the horizontal (see broken lines in Fig. 2). As clearly indicated in Fig. 5, the guideways 46 are limited in length so that the T-shaped head of the lever 53 is disengaged therefrom after the lever has performed its function of breaking in the door and the door is free to open. The bracket 52, together with its arm 69, is affixed to the upper section of the door, as 55 already explained, and consequently, as the door opens, the enlargement moves out from under the bar 49, which is then drawn by the spring 51 against the stop 50.

The last movement of the bottom section 34 upon the upper section 32 swings the bell 60 crank lever 53 in opposition to the spring

65 sufficiently to permit the arm 57 of the member 56 to pass. As soon as this arm or finger passes, the bell crank lever would be free to swing back to its initial position except that it is held substantially in the position shown in Fig. 5 by the latch 71 which has been cammed back by the upward movement of the latch 54 and now holds both the latch 54 and the lever 53 in an inclined position with the springs 65 and 66 under tension.

From this point the door swings open in the usual manner and the mechanism performs no function until the door approaches the position shown in Fig. 5 in closing.

In closing the door the hand chain is actuated in the reverse direction and the door sections swing downwardly coming into the position of Fig. 5 except that the bar 49 is now in position to actuate the latch 71 by 85 engaging the beveled surface 73. This will be apparent by an inspection of Figs. 5 and 6.

When the T-shaped end of the lever 53 has engaged the guideways 46 and the bell 90 crank lever has been released from the pawl 71, the bell crank lever swings about the point of contact between the T-shaped end and the guideways by reason of the action of the spring 65 as already explained, with the 95 result that the doors are forceably swung against the door casing and into the position shown in Fig. 3. In the meantime, the lower section 34 has advanced downwardly so as to release the latch 54 which is then in 100 readiness to engage the hook projection 47 of the bracket 45, thereby securely holding the door against the casing. As soon as the lower section descends to the position shown in Fig. 2, the door is completely closed.

Thus, it is evident that the same mechanism constitutes a means which is dependent upon the upward movement of the lower door section for "breaking in" the door at the top and, furthermore, performs the very 110 useful and desirable function of forceably swinging the door into its closed position against the casing. The mechanism furthermore comprises a means for locking the door in its closed position as soon as this position 115 is reached.

The two difficulties which have been hereinbefore explained, although they impose many opposed conditions and forces, are both eliminated by a relatively simple and 120 compact mechanism which is entirely automatic in its operation.

The mechanism may be modified if it is not desired to forceably close the doors, as for example, where the door is protected 125 and is not subject to high wind pressure, tending to open it, or where the doors are hung in such a way that they tend to close positively. The mechanism modified in this way is shown in Figs. 9 and 10. In this 130

structure the stationary bracket 45^a has the hook projection 47 as before, but has no guideways, so that its body constitutes merely a wearing plate against which the end of the bell crank lever 53^a bears. The bracket 52^a supports the bell crank lever 53^a and the latch 54 as before, but has no arm 69 as the pawl 71 and its coöperating parts are not used.

10 The operation of the mechanism is substantially the same as already described except that after the lever 56 has released the latch 54 and actuated the bell crank lever 53^a, so as to "break in" the door, the arm or finger 57 pushes the bell crank lever out of the way and moves past its arm 63 permitting the bell crank lever to be swung back to its initial position as the door is closed, without performing any function. In this 15 case, the mechanism as already pointed out, does not assist in closing the door, but as soon as the door swings into its closed position the latch 54 engages the hook projection 47 and holds the door closed as in the 20 previously described mechanism.

Referring now to Figs. 11, 12 and 13, in which still another modification of the mechanism 44 is disclosed, the bracket 45^b is provided with a boss 74 at its upper end 25 which is recessed to provide a pocket 75 to receive the upper end of the bell crank lever 53^b. The end of the bell crank lever 53^b coöperates with the hollow boss 74 in a similar manner to that in which the T-shaped 30 end 64 of the lever 53 coöperates with the guideways 46, except that the parts only come into coöperation when the door is almost closed. This coöperation is however, sufficient in many cases to give the door the 35 required impetus to cause it to move forceably against the door casing so as to permit the latch 54 to engage the hook projection 47 of the bracket. This modification differs in another particular, from that of Figs. 1 to 40 45 8 inclusive in the construction of the actuating member 56^b which instead of having a laterally extending arm or finger 57, has a pivoted section 76 joined to the body of the arm by a hinge pin 77 and pressed against a 45 50 stop 78 by a spring 79. Furthermore, the outer end of the member 76 is notched as indicated at 80 to form a ledge 81 against which the latch 54 rests from the time the door has been "broken in" until the door 55 is closed against the casing. Then as the lower section 34 descends the overhanging finger 82 of the member 76 is cammed by the surface 83 of the bell crank lever and pushes the member 76 away so that the downward 60 movement of the door is not interfered with.

As clearly shown in Fig. 14, the mechanism of Figs. 9 and 10 is applicable to a door which is suspended and operates in a different manner, the structure here shown comprising horizontal supporting rails or guide-

ways 84 which are continuously engaged by rollers 85 supported on brackets 86 near the corners of the upper door section 32^c. The lower section 34^c coöperates with guideways 36^c and is provided with actuating arms 56^c 70 corresponding to the arms 56. The mechanism 44^c is similarly arranged and performs the same functions as already described in connection with the Figs. 9 and 10. It may obviously be replaced by the mechanism of Figs. 1 to 8 or that of Figs. 11 to 15, none of the mechanisms being limited in its field of usefulness to a door having any special suspension means or structural details.

The operation of the door of Fig. 14 is similar in general, to that of the previous figures, the section 34^c being elevated to overlap the section 32^c, the door being then broken inwardly by the section of the bell 85 crank lever of the mechanism 44^c. The upper end of the door continues to move inwardly, as the rollers 85 travel on the tracks 84, until the door sections are swung into a substantially horizontal position above the 90 doorway.

It is evident that the structures illustrated may be modified in various particulars, and the mechanisms applied to doors of various types within the spirit and scope of my 95 invention, and I intend that only such limitations be imposed as are indicated in appended claims.

What I claim is:

1. The combination with a door casing 100 comprising side posts and a lintel defining the door opening, of a door comprising an upper section, links suspending the section from above the door-opening, stationary guide ways on the door posts, a lower door section adapted to coöperate with the upper section and provided with means to coöperate with the guide ways on the door posts, a stationary guide above the door-opening, a bell crank lever pivotally mounted on the 105 upper section and adapted to engage the guide above the door-opening when the door approaches its closed position, and means acting upon the bell crank lever tending to swing the top of the door closed. 110

2. The combination with a door casing comprising side posts and a lintel defining the door-opening, of a door comprising an upper section, links suspending the section from above the door-opening, stationary 120 guide ways on the door posts, a lower door section adapted to coöperate with the upper section and provided at its lower corners with means to coöperate with the guide ways on the door posts, a stationary guide above the door-opening, a bell crank lever pivotally mounted on the upper section and adapted to engage the stationary guide above the door-opening when the door approaches its closed position, and a spring attached to 125 130

the bell crank lever and tending to throw the top of the door inward against the casing when the bell crank lever engages the stationary guide above the door opening.

- 5 3. The combination with a door casing comprising side posts and a lintel defining the door-opening of a door comprising an upper section, links suspending the section from above the door-opening, stationary 70
 10 guide ways on the door posts, a lower door section adapted to coöperate with the upper section and provided with means to coöperate with the guide ways on the door posts, a stationary guide above the door-opening, a 75
 15 bell crank lever pivotally mounted on the upper section and adapted to engage the stationary guide above the door-opening when the door approaches its closed position, and means acting upon the bell crank lever 80
 20 tending to swing the top of the door closed, and means dependent upon the opening of the lower door section for actuating the bell crank lever to break in the door at the top in opening.
 25 4. The combination with a door casing comprising side posts and a lintel defining the door-opening, of a door comprising an upper section, links suspending the section from above the door-opening, stationary guide 90
 30 ways on the door posts, a lower door section adapted to coöperate with the upper section and provided at its lower corners with means to coöperate with the guide ways on the door posts, a stationary guide above the door- 95
 35 opening, a bell crank lever pivotally mounted on the upper section and adapted to engage the stationary guide above the door-opening when the door approaches its closed position, and a spring attached to the bell 100
 40 crank lever and tending to throw the top of the door inward against the casing when the bell crank lever engages the stationary guide above the door opening and means dependent upon the lower door section for actuating 105
 45 the bell crank lever in opposition to the spring for breaking in the door at the top.
 5. The combination with a door casing comprising side posts and a lintel defining the door-opening, of a door comprising an upper section, links suspending the section from above the door-opening, stationary 110
 50 guide ways on the door posts, a lower door section adapted to coöperate with the upper section and provided at its lower corners 115
 55 with means to coöperate with the guide ways on the door posts, a stationary guide above the door-opening, a bell crank lever pivotally mounted on the upper section and adapted to engage the stationary guide above the door- 120
 60 opening when the door approaches its closed position, and a spring attached to the bell crank lever and tending to throw the top of the door inward against the casing when the bell crank lever engages the stationary guide 125
 65 above the door opening, and an arm attached

to the lower door section for actuating the bell crank lever to break in the door at the top when the lower door section overlaps the upper section in opening.

6. The combination with a door casing 70 comprising side posts and a lintel defining the door-opening, of a door comprising an upper section having guideways near its edges, a lower section adapted to slide upon the upper section and coöperate with said 75 guideways, links suspending the upper section from above the door-opening, stationary guideways on the door posts, rollers at the lower corners of the lower section co-operating with the stationary guideways on 80 the door posts, a stationary guide bracket secured above the door opening and having a hooked projection, a bell crank lever pivotally mounted on the upper edge of the upper door section and having one arm adapted to 85 coöperate with the guide bracket, a latch co-axially pivoted with said bell crank lever and adapted to engage said hooked projection for holding the door against the casing at the top, a spring acting upon the 90 bell crank lever to force the door closed at the top when the bell crank arm engages the guide bracket, an arm attached to the lower door section and adapted to release the latch and actuate the bell crank lever in 95 opposition to the spring to break in the door at the top and release the bell crank lever from the guide bracket, a latch supported by the upper door section for holding the bell crank lever in position to coöperate 100 with the guide bracket in closing, and a releasing lever pivotally mounted above the door-opening for tripping the holding latch when the bell crank lever engages the bracket in closing. 105
 7. The combination with a door casing comprising side posts and lintel defining the door-opening, of a door comprising an upper section, a lower section adapted to slide upon the upper section, means for 110 suspending the door to permit it to swing out of a vertical position above the door-opening, a stationary guide bracket secured above the door-opening and having a hooked projection, a bell crank lever pivotally 115 mounted on the upper door section and having one arm adapted to coöperate with the guide bracket, a latch co-axially pivoted with said bell crank lever and adapted to engage the said hooked projection for holding the door closed at the top when the bell crank arm engages the guide bracket, an arm attached to the lower door section and adapted to release the latch and actuate the bell crank lever in opposition to the spring 120 to break in the door at the top and release the bell crank lever from the guide bracket, a latch supported by the upper door section for holding the bell crank lever in position to coöperate with the guide bracket in clos- 125
 130

ing, and a releasing lever pivotally mounted above the door-opening for tripping the holding latch when the bell crank lever engages the bracket in closing.

5   8. The combination with a door casing comprising side posts and a lintel defining the door-opening, of a door comprising an upper section, a lower section adapted to slide upon the upper section, means for suspending the door to permit it to swing out of a vertical position above the door-opening, a stationary guide bracket secured above the door-opening and having a hooked projection, a bell crank lever pivotally mounted on the upper section and having one arm adapted to coöperate with the guide bracket, a latch adapted to engage said hooked projection for holding the door against the casing at the top, resilient means 10 acting upon the bell crank lever to force the door closed at the top when the bell crank arm engages the guide bracket, an arm attached to the lower door section and adapted to release the latch and actuate the bell 15 crank lever in opposition to the resilient means to break in the door at the top and release the bell crank lever from the guide bracket, a latch supported by the upper door section for holding the bell crank lever in position to coöperate with the guide bracket in closing, and a releasing lever pivotally mounted above the door-opening for tripping the holding latch when the bell crank lever engages the bracket in closing.

20

25

30

35 9. The combination with a door casing comprising side posts and a lintel defining the door-opening, of a door comprising an upper section, a lower section adapted to slide upon the upper section, means for suspending the door to permit it to swing out of a vertical position above the door-opening, a stationary guide bracket secured above the door-opening and having a hooked projection, a bell crank lever pivotally mounted 40 on the upper door section and having one arm adapted to coöperate with the guide bracket, a latch adapted to engage said hooked projection for holding the door against the casing at the top, resilient means 45 acting upon the bell crank lever and causing it to force the door closed at the top when the bell crank arm engages the guide bracket, an arm attached to the lower door section and adapted to release the latch 50 and actuate the bell crank lever in opposition to the said resilient means to break in the door at the top and release the bell crank lever from the guide bracket. 55

60 10. The combination with a door casing comprising side posts and a lintel defining the door-opening, of a door comprising an upper section having guideways near its edges, a lower section adapted to slide upon the upper section and coöperate with said guideways, links suspending the upper sec-

tion from above the door-opening, stationary guideways on the door posts, rollers at the lower corners of the lower section co-operating with the stationary guideways on the door posts, a stationary guide bracket 70 secured above the door-opening and having a hooked projection, a bell crank lever pivotally mounted on the upper edge of the upper door section and having one arm adapted to co-operate with the guide bracket, 75 a latch co-axially pivoted with said bell crank lever and adapted to engage said hooked projection for holding the door against the casing at the top, a spring acting upon the bell crank lever to force the 80 door closed at the top when the bell crank arm engages the guide bracket, a lever attached to the lower door section and adapted to release the latch and actuate the bell crank lever in opposition to the spring to 85 break in the door at the top and release the bell crank lever from the guide bracket.

11. The combination with a door casing comprising side posts and a lintel defining the door-opening, of a door comprising an upper section, a lower section adapted to slide upon the upper section, means for suspending the door to permit it to swing out of a vertical position above the door-opening, a stationary guide bracket secured above the door-opening and having a hooked projection, a bell crank lever pivotally mounted on the upper door section and having one arm adapted to coöperate with the guide bracket, a latch co-axially pivoted with said crank lever and adapted to engage said hooked projection for holding the door against the casing at the top, a spring acting upon the bell crank lever and causing it to force the door closed at the top when the bell crank arm engages the guide bracket, an arm attached to the lower door section and adapted to release the latch and actuate the bell crank lever in opposition to the spring to break in the door at the top and release the bell crank lever from the guide bracket. 110

12. The combination of a door casing comprising side posts and a lintel defining the door-opening, of a door comprising an upper section, a lower section adapted to slide upon the upper section, means for suspending the door to permit it to swing out of a vertical position above the door-opening, a stationary guide bracket secured above the door-opening and having a hooked projection, a bell crank lever pivotally mounted on the upper door section and having one arm adapted to coöperate with the guide bracket, a latch adapted to engage said hooked projection for holding the door against the casing at the top, resilient means acting upon the bell crank lever to force the door closed at the top when the bell crank arm engages the guide bracket, an 115
120
125
130

arm attached to the lower door section and adapted to release the latch and actuate the bell crank lever in opposition to the resilient means to break in the door at the top and 5 release the bell crank lever from the guide bracket.

13. An attachment for multi-section doors comprising, for the upper door section, a bell crank breaking-in lever, a spring tending to hold said lever in a retracted position and a latch for holding the lever in its actuated position, for the lower door section, an actuating lever having a spring-pressed finger adapted to coöperate with one arm of 10 the bell crank lever, and a stationary guide bracket adapted to coöperate with the other arm of the bell crank lever.

14. An attachment for multi-section doors comprising for the upper door section, a bell crank breaking-in lever, a spring tending to hold said lever in a retracted position and a latch for holding the lever in its actuated position, and for the lower door section, an actuating lever adapted to coöperate 25 with one arm of the bell crank lever.

15. An attachment for multi-section doors comprising, for the upper door section, a bell crank breaking-in lever, a spring tending to hold said lever in a retracted position and a latch for holding the lever in its actuated position, for the lower door section, an actuating lever having a spring-pressed finger adapted to coöperate with one arm of 30 the bell crank lever, and a stationary guide bracket adapted to coöperate with the other arm of the bell crank lever, and a release arm pivotally mounted on the stationary bracket adapted to release the latch.

16. The combination with a door casing 40 comprising side posts and a lintel defining a door opening, of a door section, means for suspending said section arranged to cause it

to swing out of a vertical position above the door opening in opening and to permit it to swing back into a vertical position in closing, and an elongated pivotal member engageable with a rigid member, the pivot and rigid member being mounted on the door section and the casing, one on one and the other on the other, so that the member may 45 be canted transversely to the door by relative movement of said rigid member or pivot, or of the pivoted member pivotally with relation to either, and arranged to force the top of the door section against the 50 lintel in closing.

17. The combination with a door casing comprising side posts and a lintel defining a door opening, of an upper door section, a lower door section, guide connections between the door sections to provide for the lower door section being raised up beside the upper section, means for suspending said sections arranged to cause them to swing out of a vertical position above the 60 door opening in opening and to permit them to swing back into a vertical position in closing, and an elongated pivotal member engageable with a rigid member, the pivot and the rigid member being mounted 65 on the door section and the casing, one on one and the other on the other, so that the member may be canted transversely to the door by relative movement of said rigid member, or pivot, or of the pivoted member 70 pivotally with relation to either, and arranged to force the top of the door section against the lintel in closing, the pivoted member being controlled by the motion of the lower door section relative to the upper 75 section.

In witness whereof, I have hereunto set my hand this 24th day of March, 1916.

ARTHUR T. PRESCOTT.
